UNITED STATES PATENT OFFICE.

ISAAC SNOW, OF LAWRENCE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed March 16, 1922. Serial No. 544,072.

To all whom it may concern:

Be it known that I, ISAAC SNOW, a citizen of the United States, residing at Lawrence, in the county of Essex and State of Massachusetts, have invented an Improvement in Warp Stop Mechanisms for Looms, of which the following description, in connection with the accompanying drawings, is a specification, like characters on the drawings representing like parts.

This invention relates to warp stop mechanisms for looms.

Looms are now ordinarily supplied or equipped with some kind of a warp stop motion which is intended to arrest the operation of the loom when a warp thread breaks or becomes too slack for weaving purposes. It will happen at times during weaving that a warp thread will become crossed over other warp threads and produce defective cloth unless the condition is remedied. Such crossing of a warp thread may occur when a warp thread breaks between the shedding mechanism and the fell of the cloth. In such case the broken end of the warp thread is liable to extend laterally of the loom and cross several of the warp threads of one of the shed planes, and when the shed is changed by the shedding mechanism, the crossed end of the broken warp thread will deflect the warp threads of the other plane of the shed and cause increased tension to be exerted on the warp threads of that plane. Should the weaving operation continue under such condition defective cloth will be produced and therefore one of the purposes of the present invention consists of means for effecting loom stoppage when a drop wire of the warp stop mechanism is abnormally raised by a warp thread.

It is also desirable to stop the loom when one of the warp threads breaks or becomes too slack for weaving purposes, and another important feature of the present invention therefore consists of a warp stop mechanism in which two feelers are employed, one of which is adapted to be arrested and effect

loom stoppage when a drop wire is abnormally raised and the other of which is adapted to be arrested and effect loom stoppage when a drop wire is abnormally lowered as by breakage or undue slackage of a warp thread.

The accompanying drawings illustrate one good form of the invention wherein one of the feelers is constructed and arranged to be arrested in its detecting movement above the plane of the warp threads and the other of which is adapted to be arrested in its detecting movement below the plane of the warp threads; and while this constitutes a good form of the invention the essential advantages thereof may be secured by other arrangements of the feelers and drop wires.

In the drawings, Fig. 1 is a perspective view showing sufficient portions of a loom to make clear the association of the present invention therewith.

Fig. 2 is an enlarged cross sectional view of the warp stop mechanism proper.

Fig. 3 is a detached enlarged detail showing one means for giving the two feelers their detecting movements.

Fig. 4 is a modified form of means for giving the two feelers their feeling movements.

It is the object of warp stop motions, as now generally constructed, to stop the loom whenever a warp thread breaks. This functional operation of the warp stop motion is dependent on the release of some kind of a detector or drop device by the broken warp thread which becomes too slack to support the drop device or detector. It sometimes happens, however, that the end of the broken thread gets crossed laterally of the adjacent intact warp threads and is held taut or does not slacken sufficiently to free the drop device or detector, and in such case these prior warp stop motions fail to function even though a warp thread breaks.

The warp stop mechanism of the present invention includes a series of drop wires which are normally supported by the warp

threads during weaving and which are free to move into an abnormal position either by breakage or by undue slackness of a warp thread or into another abnormal position by 5 undue tension of the warp thread, the two feelers are constructed and arranged, one to effect loom stoppage when a drop wire moves into one abnormal position upon 10 breakage or undue slackage of a warp thread and the other feeler of which is arrested when a drop wire is moved into the other abnormal position by undue tension exerted on a warp thread.

The warp threads *a* are wound upon the 15 usual warp beam 1, Fig. 1, supported in bearings carried by the loom frame and such warp threads pass from the warp beam and over the usual whip roller 2 the opposite end portions of which are supported in 20 brackets 3. From the whip roller 2 or other guide device for warp threads, the warp threads pass forwardly or frontly through the warp stop motion proper, either with or without being positioned by the lease 25 rods, then through the shedding mechanism by which the warp threads are divided into appropriate sheds from time to time, then through the reed of the lay and forwardly to the fell of the cloth or weaving line and thence to the usual sand roller or take up. 30

The loom frame is of usual character appropriate for supporting the loom parts and has a breast beam 4 to which is secured the temple 5 which engages the cloth *b* at the 35 point rearward of the usual sand or take up roll 6. The lay 7 has the usual reed 8 through which the warp threads pass as usual, and the lay is given its usual beat up movements by a well known train of mechanism. 40

The shedding mechanism for producing a shed for the introduction of the weft or filling thread may be of any usual and well known type and as indicated in Fig. 1 comprises the harness forms 9 and 10 between the upper and lower bars of which are the heddles 11 each having an eye for the passage of a warp thread as usual. The mechanism for forming the shed is not shown because the details thereof form no part of the present invention and may be of the usual and well known character. 45

The warp stop motion proper as shown in Fig. 1 is positioned between the shedding mechanism and the whip roll and is supported on suitable brackets 12 extending from each side of the loom frame. To facilitate adjustment of the warp stop mechanism proper into its desired position the brackets 55 12 may be provided with slots 13 engaged by bolts 14 passed through the slots 15 of side brackets 16 one at each side of the loom. Since each of the side brackets 16 may be of the same construction it will not be necessary 60 to describe more than one.

The side bracket 16 in the present instance carries the side member 17 and the two side members, one at each side of the loom, are connected by the warp rest members 18. The members 18 may be secured to the side 70 members 17 by screws or other means 19 and are conveniently formed and shaped so that the warp threads *a* may rest upon the top surfaces of the warp rest members 18 as indicated in Fig. 2 when the drop wires are 75 in normal weaving position.

Between the warp rest members 18 are the drop wires 20, two rows of such drop wires being shown in the present instance. Each drop wire 20 is normally supported by a 80 warp thread *a* during weaving and in the present instance each drop wire has an opening or eye 21 through which the warp thread may be passed. The drop wires are guided in their movements and as shown each drop 85 wire in the present instance has an elongated slot 22 through which extends one of the drop wire guides 23, the construction being such that the drop wires 20 which are arranged in rows may be guided in their up 90 and down movements for the action of the feelers, presently to be described. The thread guides 23 are secured at each side of the loom to the side members 17 as indicated in Fig. 1. 95

In accordance with the present invention the loom is to be stopped when one of the drop wires drops or is freed from its warp support by the breakage or undue slackness of a warp thread and also when one of the 100 drop wires is moved into another abnormal position by undue tension on a warp thread. This feature of the invention is carried into effect by two feelers one of which is arrested by an abnormally raised drop wire and the 105 other of which is arrested by an abnormally lowered drop wire.

In the present instance the warp rest members 18 are each provided with the tooth plates 24 and mounted for detecting movement towards and from the plates 24 is the feeler 25. The feeler 25 is shown as having a toothed edge portion 26 at each side adapted to engage and be arrested by one of the drop wires when it fails to be supported 110 by a warp thread. The feeler 25 is secured to rocker arms 27 of which there may be a suitable number to properly support the feeler between the sides of the loom. The feeler rocking arms 27 are mounted upon the 115 rocker 28 which receives a rocking movement, as usual in warp stop motions, from some going part of the loom. In the present instance the rocker 28 has the lugs 29, Fig. 2, which are connected by links 30 to a 120 train of mechanism for imparting to the rocker 28 and perforce the feeler 25 the feeler or detecting movement. The train of mechanism to which reference has been made 125 may be of the general type of that shown 130

and described in the patent to George B. Ambler, No. 863,130, August 13, 1907, but any well known trains of mechanism for giving the feeler its detecting movement may be employed. In the present instance of the invention the stopping mechanism comprises means for arresting the loom operation when one of the feelers is arrested. Such stopping mechanism is typified in Fig. 1 by the shipper 31 which may be thrown from its holding notch 32 to effect loom stoppage substantially as indicated in the Ambler patent hereinbefore mentioned.

The rocker arm 27 at the side of the loom is shown as outside of the bracket or downward extension 33 of side member 17 by which the rocker is supported, and in such case the portion 33 is provided with a slot 34 through which the feeler 25 extends. The slot is of appropriate size and character to permit the feeler to partake of its detecting movements.

Extending transversely of the loom, and as shown in the present instance, between the warp rest members 18 is a rod or shaft 35 on which is mounted for rocking movement the other feeler member which acts to effect loom stoppage when one of the drop wires is abnormally raised by a warp thread unduly tensioned. In the form of the invention indicated in Figs. 1 and 2 the rod or shaft 35 extends outside of side members 17 and has mounted thereon the feeler 36, the upper portion 37 of which extends transversely of the loom adjacent to the upper end portions of the drop wires. The side members of the feeler 36 or at least one of them has a downward extension 38 which passes through an opening 39 in the bracket 16 and at its lower end is connected with the other feeler.

In the present instance the feeler 36 is connected to the feeler 25 through the extension 38, Fig. 3, the lower end portion of which is loosely connected to the lugs 39 carried by the train of mechanism constituting the lower feeler. The lugs or bearings 39 have an enlarged opening 40 through which passes the pin 41, Fig. 3, for connecting the extension 38 with the lower feeler.

From the construction thus far described it will be apparent that the detecting movement given to the lower feeler 25 will impart detecting movements to the other or upper feeler and that such movements of the two feelers will be in opposite directions. In other words, when feeler 25 moves to the left, Fig. 2, feeler 36 will move to the right, and if either feeler be arrested by a drop wire it will act through the train of stop mechanism to effect loom stoppage.

Fig. 4 shows a modified form of the connections between the two feelers whereby both feelers will move simultaneously in the same direction rather than in the opposite

direction, as effected by the hereinbefore described connections between the two feelers. In Fig. 4 the rocker 28 which is the same as the rocker of Fig. 2 carries the feeler arms 42 of which there may be any desired number, to which is secured the lower feeler 43.

The rocker 28 is given its rocking movement by the train of mechanism such as is shown for instance in the patent to Ambler hereinbefore mentioned. In Fig. 4 the rocker 28 has an arm 44 connected by a link 45 with an arm 46 extending from the hub portion of the upper feeler supporting arm 47 carrying the rod or feeler 48. The arms 46 and 47 are mounted on the rod or shaft 49, Fig. 4, the construction being such that upon rocking movement of the rocker 28 the lower feeler will be given its detecting movement and the upper feeler will be given a like detecting movement in the same direction.

Should a warp thread become crossed, that is be crossed over two or more warp threads forming the shed, it will bind together the adjoining threads of the other shed plane when the shed is changed and consequently put increased tension on the threads of such other plane. This is indicated in Fig. 1 wherein the warp thread a' of the lower shed is shown as having been broken between the shedding mechanism and the reed of the lay and such end a' is indicated as crossing several of the warp threads, so that as the threads which form the upper plane of the shed are raised by the shedding mechanism the warp threads are given an increased tension or lengthwise pull due to the deflection of such threads by the crossed warp end. The effect of this is that the warp threads that have been crossed by the broken end lift or raise the drop wires through which they pass. As indicated in Fig. 1 there are usually several warp threads given increased tension under the conditions noted and so several of the drop wires are raised. It may sometimes happen that the warp threads that form the different shed planes may be stuck together or intertwined by a stray piece of thread or by a bunch of fluff or fibre in which case the increased tension will be placed upon the warp threads thus bound together and the associated drop wires will be raised when the shed is formed.

Usually it will be sufficient to depend upon the shedding mechanism to lift the drop wires an abnormal amount or into stopping position when the shed is formed but in some cases it may be desirable to place the warp stop motion proper, slightly below the horizontal plane passing through the eyes of the heddles when the shed is closed.

From the construction described it will be clear that the present invention provides two feelers which have detecting movements,

- one to be arrested by a drop wire when it is moved into an abnormal position by the breakage or undue slackness of a warp thread and the other of which is moved into 5 another abnormal position by undue tension placed upon the warp threads, the effect being that imperfect cloth which may result from either broken or too slack threads or from a crossed warp thread will be prevented 10 because the loom will be stopped on the occurrence of either defect in the threads and enable the weaver or attendant to correct the fault.

What is claimed is:—

- 15 1. In a warp stop mechanism for looms, the combination of a series of drop wires normally supported by the warp threads during weaving, loom stopping mechanism, two feelers having detecting movements, one 20 above and the other below the plane of the warp threads, and connections between the feelers and stopping mechanism for stopping the loom when a drop wire is raised to an abnormal position by a warp thread 25 or is lowered to an abnormal position due to breakage or slackness of a warp thread. 2. In a warp stop mechanism for looms, the combination of a series of drop wires normally supported by the warp threads 30 during weaving, two feelers having detecting movements, one of which feelers is constructed and arranged to be arrested when a drop wire is abnormally raised by a warp thread and the other of which is constructed 35 and arranged to be arrested by a drop wire when a warp thread breaks or becomes too slack, and stopping mechanism for stopping the loom when the detecting movement of either of the feelers is arrested. 40 3. In a warp stop mechanism for looms, the combination of a series of drop wires adapted to be supported by the warp threads during weaving, drop wire guides for the series of drop wires, two feelers having 45 detecting movements, one of said feelers adapted to engage and be arrested by a drop wire when it is raised to an abnormal position, and the other to engage and be arrested by a drop wire when it is lowered 50 to an abnormal position, and stopping mechanism for stopping the loom when either of the feelers is arrested. 4. In a warp stop mechanism for looms, the combination of shedding mechanism, a 55 series of drop wires adapted to be supported by the warp threads during weaving, a feeler having a detecting movement above the plane of the warp threads and adapted to be arrested by a drop wire when it is 60 abnormally raised by a warp thread, and loom stopping mechanism for stopping the loom when the feeler is arrested by an abnormally raised drop wire. 65 5. In a warp stop mechanism for looms, the combination of shedding mechanism, a

series of drop wires adapted to be supported by the warp threads during weaving, a feeler having a detecting movement above the plane of the warp threads and adapted to be arrested by a drop wire when it is abnormally raised by a warp thread, another feeler having a detecting movement and adapted to be arrested by a drop wire when a warp thread breaks or becomes too slack, and loom stopping mechanism for stopping the loom when either feeler is arrested by a drop wire. 70 75 80

6. In a warp stop mechanism for looms, the combination of a series of drop wires adapted to be supported by the warp threads during weaving, loom stopping mechanism, two feelers one of which has a detecting movement adjacent the upper portions of the drop wires and the other of which has a detecting movement adjacent the lower 85 portions of the drop wires, and means controlled by the two feelers to cause the stopping mechanism to effect loom stoppage when either of the feelers is arrested by a drop wire. 90

7. In a warp stop mechanism for looms, the combination of a series of drop wires adapted to be supported by the warp threads during weaving, loom stopping mechanism, two feelers one of which has a detecting 95 movement adjacent the upper portions of the drop wires and the other of which has a detecting movement adjacent the lower portions of the drop wires, connections between the feelers and means controlled by the two feelers to cause the stopping mechanism to effect loom stoppage when either of the feelers is arrested by a drop wire. 100

8. In a warp stop mechanism for looms, the combination of a series of drop wires adapted to be supported by the warp threads during weaving, loom shedding mechanism, two feelers having detecting movements toward and from the drop wires, the detecting movement of one of the feelers being arrested when a drop wire is abnormally raised and the detecting movement of the other feeler being arrested when a drop wire is abnormally lowered, and loom stopping mechanism for stopping the loom when the detecting movement of either feeler is arrested. 105 110 115

9. In a warp stop mechanism for looms, the combination of a series of drop wires adapted to be supported by the warp threads during weaving, loom shedding mechanism, a feeler having a detecting movement and adapted to be arrested by an abnormally raised drop wire when the shed is opened, loom stopping mechanism for stopping the 120 loom when a drop wire is abnormally raised and another feeler adapted to be arrested and effect loom stoppage when a warp thread breaks or becomes too slack. 125 130

10. In a warp stop mechanism for looms,

the combination of a series of drop wires adapted to be supported by the warp threads during weaving, drop wire guides for the drop wires, two feelers, one of which is adapted to engage and be arrested by a drop wire above the plane of the warp thread and the other of which is adapted to engage and be arrested by a drop wire below the plane of the warp threads, and loom stopping mechanism for stopping the loom when either of the feelers is arrested.

In testimony whereof, I have signed my name to this specification.

ISAAC SNOW.
